UNITED STATES PATENT OFFICE.

CHESMAN B. ZELLER, OF WICHITA, KANSAS.

COTTER-PIN EXTRACTOR.

Application filed October 8, 1923. Serial No. 667,272.

To all whom it may concern:

Be it known that CHESMAN B. ZELLER, a citizen of the United States, residing at Wichita, in the county of Sedgwick and 5 State of Kansas, has invented certain new and useful Improvements in Cotter-Pin Extractors, of which the following is a specification.

This invention relates to new and useful 10 improvements in cotter pin extractors and has for its principal object to provide a tool which will readily and easily remove cotter pins from various parts of machinery in a manner which will prevent the machinery 15 from becoming damaged due to the use of the tool in extracting the cotter pins.

Another important object of the invention is to provide a cotter pin extractor of the above mentioned character, wherein means 20 is provided for enabling the head of the cotter pin to be supported in position so as to enable the extractor to readily disengage the pin from its seated position.

Another important object of the invention 25 is to provide a cotter pin extractor of the above mentioned character, which can be readily and easily adjusted to engage the cotter pin and is furthermore provided with a handle whereby the cotter pin may be 30 quickly removed from its seated position regardless of how fast the cotter pin may be secured in the machinery.

A still further object of the invention is to 35 provide a cotter pin extractor which is simple in construction, inexpensive, strong, durable and further well adapted for the purposes for which it is designated.

Other objects and advantages of this invention will become apparent during the 40 course of the following description.

In the accompanying drawings forming a part of this specification and in which like numerals designate like parts throughout the same:—

45 Figure 1 is a central vertical section of my cotter pin extractor showing the same in use.

Figure 2 is a side elevation of the extracting member or rod, and

Figure 3 is a detail view of the handle.

50 In the drawings wherein for the purpose of illustration is shown the preferred embodiment of my invention, the numeral 1 designates an elongated tubular member which is formed of any suitable material. 55 Slidably mounted in the tubular member 1 is the elongated extracting rod 2. The up-

per portion of the rod 2 is externally threaded as shown at 3 in the drawings and the lower end terminates into a hook portion 4. The extracting member or rod 2 is furthermore provided with a longitudinally extending slot 5 provided in the lower portion of the same in a manner as more clearly shown in Fig. 2 of the drawings and for the purpose to be hereinafter more fully described. 60 65

The extracting rod 2 is adapted to be received in the tubular member 1 and when in position therein the upper threaded end is adapted to extend beyond the upper end of the tubular member 1 in the manner as 70 more clearly shown in Fig. 1 of the drawings and the purpose of this arrangement is to provide a means for permitting the internally threaded head 6 of a suitable handle 7 to be threaded thereon whereby a 75 means is provided for actuating the elongated extracting rod 2 in the tubular member 1.

In order to prevent the extracting rod 2 from rotating when the same is in use and 80 operation, the tubular member 1 is provided intermediate its ends with the registering apertures 8 which are arranged diametrically opposite each other and adapted to be seated in these registering apertures 8 and extending through the longitudinal slot 5 provided in the lower portion of the extending rod 2 is the pin 9. The free ends of the pin 9 may be bent downwardly 85 against the outer faces of the tubular member so as to prevent accidental displacement of the pin when in position therein. The pin 9 will extend through the slotted portion of the extracting member 2 and will 90 prevent the same from rotating in the tubular member although it will permit the rod to be moved longitudinally therein.

In use, with the parts arranged as shown in Fig. 1 of the drawings, the hook portion 4 of the extracting rod 2 extends beyond the lower end of the tubular member 1 and is adapted to engage the head of the cotter pin in the well known manner. When in this position the hook portion 4 of the extracting rod 2 extends beyond the lower end 95 of the tubular member 1 and is adapted to engage the head of the cotter pin in the well known manner. Upon rotation of the handle 7, the threaded portion 3 of the extracting member 2 will be caused to move upwardly through the tubular member 1 and the threaded head 6 of the handle and at

the same time cause the hook portion 4 to be drawn into the bottom portion or end of the tubular member 1 simultaneously causing the cotter pin to be withdrawn from its clinched or seated position in the particular part in which it is used. It will be further understood that the bottom face of the lower end of the tubular member 1 will act as a seat for the cotter pin extracting tool and will engage the surface of the machinery and the head of the cotter pin will be caused to be drawn into the lower portion of the tubular member 1 upon vertical movement of the extractor rod 2. The pin 9 will act as a guide means for the extractor rod 2 when the same is moved longitudinally within the tubular body and will furthermore prevent the rotation of the same therein.

It will thus be seen from the foregoing description that a cotter pin extractor has been provided wherein the various parts may be easily and quickly set up in position for use and does not require the employment of auxiliary or extra tools in order to remove the cotter pin from its seated position in the various parts of the machinery. Furthermore the simplicity with which my cotter pin extractor is operated enables the same to readily and easily remove cotter pins which have become clinched and are very hard to be removed and furthermore considerable time is saved in removing the cotter pins.

From the foregoing description of the

construction of my improved apparatus, it will be seen that I have provided a simple, inexpensive and efficient means for carrying out the objects of the invention, and while I have particularly described the elements best adapted to perform the functions set forth, it is obvious that various changes in form, proportion and in the minor details of construction may be resorted to, without departing from the spirit or sacrificing any of the principles of the invention.

What I claim as new and desire to secure by Letters Patent is:—

A cotter pin extractor of the class described, including a tubular body member, an extracting rod slidably mounted therein, said extracting rod provided with a hook at its lower end, the upper portion of said rod being threaded externally and the upper end thereof adapted to extend beyond the upper end of said tubular body member, a handle threaded on the upper end of said rod for actuating the same longitudinally in said tubular body member, said rod provided with a longitudinal slot in its lower portion, and a pin carried by said tubular body member and extending transversely through said longitudinal slot for permitting the longitudinal movement of said rod in said tubular body member but preventing the rotation of said rod in said tubular body member.

In testimony whereof I affix my signature,
CHESMAN B. ZELLER.
